US00D925968S

(12) **United States Design Patent** (10) **Patent No.:** **US D925,968 S**
Lin (45) **Date of Patent:** **** Jul. 27, 2021**

(54) **MEAT GRINDER**

(71) Applicant: **GUANGZHOU LIVING HARDWARE AND PLASTIC MANUFACTURING CO., LTD,**
 Guangzhou (CN)

(72) Inventor: **Shuyuan Lin**, Jiangmen (CN)

(73) Assignee: **GUANGZHOU LIVING HARDWARE AND PLASTIC MANUFACTURING CO., LTD,**
 Guangzhou (CN)

(**) Term: **15 Years**

(21) Appl. No.: **29/753,566**

(22) Filed: **Sep. 30, 2020**

(30) **Foreign Application Priority Data**

Primary Examiner — Ricky Pham

(57) **CLAIM**

The ornamental design for a meat grinder, as shown and described.

DESCRIPTION

FIG. 1 is a perspective view of a meat grinder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are for illustrative purposes only and form no part of the claimed design.

1 Claim, 8 Drawing Sheets
